ILLUMINATED GREETING CARD

Winslow B. Pope, Detroit, Mich.

Application June 10, 1946, Serial No. 675,800

5 Claims. (Cl. 40—132)

1

This invention relates to an illuminated greeting card.

It is an object of this invention to produce an illuminated greeting card which is of simple structure, inexpensive, and easy to operate.

In the drawings:

Fig. 1 is a front elevation of my card.

Fig. 2 is a section along the line 2—2 of Fig. 1.

Fig. 3 is a detail of the switch.

Fig. 4 is a front elevation of a modified form of my greeting card.

Fig. 5 is a section along the line 5—5 of Fig. 4.

Figs. 6 and 7 are details of the switch which automatically completes the lighting circuit when the cover is removed.

Fig. 8 is a section through another modified form of my greeting card.

Referring more particularly to the drawings, it will be seen that my greeting card comprises a triangular box member 1 of fiber board, such as paper or cardboard. Box 1 preferably comprises a single piece of cardboard folded along lines 2 and 3 to form a triangular cross section. The meeting ends overlap and are glued or otherwise secured together as at 4. Box 1 is also preferably provided with end walls 8. The front wall 5 is provided with an opening 6 which is closed by a transparency or window 7 of transparent tissue paper or plastic such as Celluloid. The transparent window 7 has printed, painted, cut-out of, or otherwise fashioned thereon a greeting plus a picture suitable for the season or occasion, such as Christmas, Easter, or a birthday, for which the greeting is designed. The inner face of the back wall 9 of my greeting is provided with a reflector 10 of tin foil, aluminum foil, or other light reflecting material which also extends across the inner surface of the base 11, passing under battery 12 and bulb 13, and on up the inner face of the front wall 5 as far as opening 6, thus reflecting a maximum amount of light through the transparent window 7.

The lighting circuit which is mounted within the box 1 and upon the base 11 thereof comprises a dry-cell battery 12, an incandescent lamp or bulb 13, wires 14 and 15 and a switch comprising a stationary contact 16 and a manually operable or rotatable contact 17 having an integral handle 18. When switch contact 17 is brought into contact with stationary contact 16, the circuit through light 13 is completed so that the light from bulb 13 directly and also reflected by reflector 10 passes through the transparent window 7 and illuminates the picture and greeting thereon.

In the modified form shown in Figs. 4 and 5,

2

my greeting card comprises a rectangular box 19 having an opening 20 in the front wall thereof. The back wall 21 is provided with a tin or aluminum reflector 22 and lighting components identical with that shown in Fig. 1 except that the circuit is provided with two light bulbs 23 connected in a parallel electrical circuit.

In this form of greeting card the transparent paper tissue or plastic background 24, which has composed thereon the greeting and any suitable picture, is positioned between opening 20 and back wall 21 by the agency of internal support 38. In the foreground there are provided a plurality of opaque spaced inserts 25, 26 and 27 which are held in an upright position by means of sub-base 40 of internal support 38. The spaced inserts 25, 26 and 27 are illuminated by light from bulb 13 passing through openings 39 contained in sub-base 40. The inserts are of varying contours and increase in height from window 20 toward transparency 24, that is, inserts 25, 26 and 27 are of decreasing height in that order so as to give an illusion of depth or perspective.

In the form of box shown in Figs. 6 and 7, the structure is identical with that shown in Fig. 4 except that box 19 is provided with a cover 30 which closes opening 20. The peripheral flange 31 of cover 30 overlaps the sides of box 19. Instead of manual switch 18 with contacts 16 and 17, there is provided a spring contact arm 32 and a fixed contact 33. The end of spring contact arm 32 is provided with a cam 34 which projects through an opening 35 in a side wall of box 19. Thus, when cover 30 is positioned upon box 19, flange 31 engages cam 34, as shown in Fig. 7, and contact 32 is out of contact with stationary contact 33 and the circuit is broken. When cover 30 is removed, spring contact arm 32 engages contact 33 to close the circuit between battery 12 and lights 23 to thereby cause the lights to incandesce and illuminate the greeting as above described.

Thus, greeting card 19 with the automatic switch will be presented with the cover on and the recipient of the greeting upon removing cover 30 will cause the greeting to be automatically illuminated.

The optional design as indicated in sectional view Fig. 8 consists of a triangular box member 50 identical to that shown in Figs. 1 and 2 with the exception that opening 6 is either entirely open with no transparent closure 7, as in Fig. 1, or with certain portions of transparency 7 cutout to cause openings in said transparency. On the inner surface of the back wall 9 is fastened a

printed, painted, or otherwise formed background 50 which can be viewed through complete opening 6 if not covered, or through the partial cut-outs in transparency 7. The reflector 51 in this case only extends from opening 6 on the inner surface of front wall 5 across the inner surface of base 11 passing under battery 12 and bulb 13, and on up the inner surface of back wall 9 connecting with the lower edge of background 50.

I claim:

1. A greeting comprising a box formed of paste-board sheet material and having a window opening in the front wall thereof, a light reflecting member comprising a sheet of metal foil secured to the inner face of the back wall, an incandescent lamp between the reflector and the window, a battery, a switch controlled by means on the outside of said box, and wires connecting in circuit the battery, lamp and switch, the battery, lamp and wires being mounted within the box, and a transparent member spaced forwardly of said reflector and visible through said window opening and having a greeting formed thereon whereby when the circuit is completed by closing said switch the greeting will be illuminated.

2. The combination as set forth in claim 1 wherein said pasteboard sheet material is folded along spaced parallel lines to form a box of triangular cross section and the dry-cell battery and light are positioned upon the base of the box opposite the apex of the triangle and below the level of said window opening, said battery being positioned such that it extends lengthwise along said base.

3. A greeting as described in claim 1 including a removable cover for said box, means for

controlling said switch being actuated by the removal of said cover for closing the switch and by the placing of said cover upon the box for opening the switch to break the lighting circuit.

5. The combination as set forth in claim 1 including a cover for said box, a stationary and a movable contact in said lighting circuit, said means for controlling said switch including a cam on the movable contact adapted to engage the cover when placed on said box for breaking the lighting circuit, and means for closing the movable contact and stationary contact when the cover is removed from the box and out of engagement with said cam.

10 6. The combination as set forth in claim 1 wherein said metal foil reflecting member extends downwardly along said back wall and across the bottom wall of the box below said lamp and upwardly along the front wall of the box toward said window opening.

WINSLOW B. POPE.
